RESPIRATOR

Ted Allen Bell, Pittsburgh, and Glenn W. Monigle, Bradfordwoods, Pa., assignors, by mesne assignments, to Mine Safety Appliances Company

Filed Dec. 11, 1967, Ser. No. 9,716

Term of patent 14 years

Int. Cl. D24—02

U.S. Cl. D83—1

Fig. 1.

Fig. 2.

Fig. 3.

Fig. 4.

Fig. 5.

Fig. 6.

Fig. 7.

FIG. 1 is a front elevation of a respirator showing our new design;

FIG. 2 is a side elevation thereof, the opposite side is a mirror image of the side shown;

FIG. 3 is a top plan view thereof;

FIG. 4 is a rear elevation thereof;

FIG. 5 is a bottom plan view thereof;

FIG. 6 is a perspective view as seen from the side and front of FIG. 1;

FIG. 7 is a perspective view as seen from the bottom and rear of FIG. 1.

The strap members have been omitted in FIGS. 1, 3, 4, 6 and 7 and broken away in FIGS. 2 and 5 for ease of illustration.

We claim:

The ornamental design for a respirator, as shown and described.
